Fig. 4

Fig. 1 is a front perspective view of a vehicle jack embodying my new design;

Fig. 2 is a side elevational view of the vehicle jack taken from the left side of Fig. 1;

Fig. 3 is a rear elevational view thereof; and

Fig. 4 is a top plan view of the vehicle jack.

The characteristic features of my design for the vehicle jack disclosed reside in the appearance of the specific handle, battery housing, and electric motor housing associated with the rear of the jack frame, as shown.

I claim:

The ornamental design for a vehicle jack, substantially as shown and described.
